UNITED STATES PATENT OFFICE

103,408

DESIGN FOR A GARDEN CHAIR

Henry R. Reischmann, New York, N. Y.

Application January 8, 1937, Serial No. 66,943

Term of patent 7 years

To all whom it may concern:

Be it known that I, Henry R. Reischmann, a citizen of the United States of America, residing in New York, in the Borough of Bronx, county of Bronx, and State of New York, have invented a new, original, and ornamental Design for a Garden Chair, of which the following is a specification, reference being had to the accompanying drawing, forming part thereof, wherein,

The figure is a front perspective view of a garden chair showing my new design.

The characteristic feature of my design resides in the rolled ends of the back rest and seat slats of the chair, as shown.

I claim:

The ornamental design for a garden chair, substantially as shown, and described.

HENRY R. REISCHMANN.
